UNITED STATES PATENT OFFICE.

HARRIS DOLID, OF NEW YORK, N. Y.

CAN OR RECEPTACLE FOR ASHES, &c.

SPECIFICATION forming part of Letters Patent No. 730,100, dated June 2, 1903.

Application filed October 3, 1902. Serial No. 125,801. (No model.)

To all whom it may concern:

Be it known that I, HARRIS DOLID, a subject of the Czar of Russia, residing at Manhattan borough, New York city, in the county of New York and State of New York, have invented new and useful Improvements in Cans or Receptacles for Ashes and other Substances, of which the following is a specification.

This invention relates to cans or receptacles, more especially of the kind used for ashes, garbage, and the like or exposed to rough handling or usage.

This invention resides in certain features of construction set forth in the following specification and claims, and illustrated in the annexed drawings, in which—

Figure 1 is a side elevation of a can or vessel embodying this invention. Fig. 2 is a central vertical section of Fig. 1. Fig. 3 is a plan view of Fig. 1. Fig. 4 is a section along xx , Fig. 1. Fig. 5 is a detail view of a plunger.

This invention relates to a receptacle for ashes and the like, having vertical hollow rods or tubes secured to the vessel and a number of plungers, each plunger being adapted to rest against a cushion of rubber placed in the interior of the tubes, so as to take up the shocks when the vessel is dropped on the ground.

The body of the receptacle is shown at a and the rods or tubes at b . These rods or tubes are fastened to the exterior of the receptacle by a number of laps c , which are riveted to the receptacle. The interior of each of the said rods or tubes is provided with a plunger e , the upper portion of which comes in contact with a rubber cushion f , the same

being braced by a core g , made of wood and filling the interior of the tube. The angle-iron rims h at the top and bottom of the vessel are riveted or secured to the vessel-body. The said plungers have secured to them the hoop i , which is placed below and out of contact with the bottom of the vessel, so that when the vessel is dropped or landed hard on the ground the plungers will give or yield and the elastic cushions take up the shock.

What I claim as new, and desire to secure by Letters Patent, is—

1. A receptacle having tubes secured thereto, fillers in said tubes, cushions seated against said fillers, and plungers placed against said cushions and projecting from the lower end of said tubes, for the purpose specified.

2. A receptacle having tubes secured thereto, fillers in said tubes, cushions seated against said fillers, plungers placed against said cushions, and a bottom support attached to said plungers.

3. A receptacle having upper and lower angle-iron rims secured thereto, tubes secured to the receptacle, fillers in said tubes, cushions and plungers seated against said fillers, and a bottom hoop secured to said plungers clear of the vessel-bottom to allow play or rebound to the hoop.

In testimony whereof I have hereunto set my hand in the presence of two subscribing witnesses.

HARRIS DOLID.
